UNITED STATES PATENT OFFICE

2,672,022

MULTICOMPARTMENT REFRIGERATING APPARATUS

James W. Jacobs, Dayton, Ohio, assignor to General Motors Corporation, Dayton, Ohio, a corporation of Delaware

Application October 24, 1951, Serial No. 252,901

6 Claims. (Cl. 62—4)

1

This invention relates to refrigerating apparatus and more particularly to refrigerators provided with cooling units in which the refrigerated outer exposed surfaces of the freezing container defrost during the idle period of the refrigerating system while the interior of the container remains at sub-freezing temperatures.

For a low cost refrigerator it is desirable that there be only a single unit for cooling the food compartment and also for freezing ice and preserving frozen foods. In the past such units have continuously accumulated frost on the exposed surface since it was necessary that the unit be operated continuously below 32° F. to freeze and preserve ice and frozen foods.

It is an object of my invention to provide a refrigerator with a box-shaped cooling unit having outer surfaces exposed to the atmosphere in the food compartment which outer surfaces are of sufficiently low mass to defrost during the idle period of the refrigerating system while the interior of the unit has sufficient mass and is sufficiently isolated that it remains at temperatures below freezing at all times.

It is another object of my invention to provide a refrigerator with a box-shaped cooling unit in which the outer walls are formed largely of metal, the greater portion of which are refrigerated for cooling the atmosphere in the food compartment while a refrigerated plate construction thermally isolated from the outer walls is provided within the cooling unit for freezing and preserving ice and frozen foods without being greatly affected by the temperatures of the outer walls.

These objects are obtained by providing a box-shaped container having the greater portion of its outer surface composed of metal walls provided by refrigerant passages. Within the container there is provided a refrigerated plate having extensive flat surfaces for supporting ice trays and frozen food products. The refrigerated plate is an integral part of the cooling unit but is thermally isolated from the outer walls and from the atmosphere in the food compartment. The outer walls have a low mass while the refrigerated plate has a high mass. The system is operated upon a defrosting cycle in response to the temperature of the outer walls of the container so that the outer walls will defrost toward the end of the idle periods of the refrigerating system while the interior always remains at temperatures below freezing.

Further objects and advantages of the present invention will be apparent from the following

2

description, reference being had to the accompanying drawings, wherein a preferred form of the present invention is clearly shown.

In the drawings:

Fig. 1 is a vertical sectional view taken substantially along the line 1—1 of Fig. 3 of a refrigerator embodying one form of my invention;

Fig. 2 is a diagrammatic developed view of the cooling unit showing the arrangement of refrigerant passages;

Fig. 3 is the sectional view taken along the line 3—3 of Fig. 1;

Fig. 4 is a diagrammatic development view of the cooling unit shown in Figs. 5 and 6 illustrating the arrangement of refrigerant passages therein;

Fig. 5 is a sectional view taken substantially along the line 5—5 of Fig. 6 showing another form of a cooling unit embodying my invention;

Fig. 6 is a sectional view taken substantially along the line 6—6 of Fig. 5;

Fig. 7 is a sectional view taken substantially along the line 7—7 of Fig. 8 showing another form of my invention; and

Fig. 8 is a sectional view taken substantially along the line 8—8 of Fig. 7.

Referring now to the drawings, there is shown an insulated refrigerator cabinet 30 including a food compartment 32 which is normally closed by an insulated cabinet door 34. Referring now more particularly to Fig. 1 there is shown a sealed motor compressor unit 28 for compressing the refrigerant and forwarding the compressed refrigerant to a condenser 22 where the refrigerant is liquefied and forwarded through a capillary restrictor tube 24 to the refrigerated plate 26 located within the box-shaped freezing container 28.

The freezing container 28 is composed of a continuously extending U-shaped metal wall portion 36 forming the sides and the bottom of the freezing container together with the back metal wall 38 and a top metal wall 40. The side U-shaped wall portions 36 extend upwardly and are provided at the top with flanges 42 and 44 fastened to the top wall of the liner 46 which encloses the food compartment 32. The enclosure of the freezing container 28 is completed by an insulated freezer door 47 which is hinged at the bottom and provided with a gasket seal so that the freezing container is completely sealed from the atmosphere in the food compartment 32 whenever the door 47 is in the closed position. The hinges on the door 47 are preferably provided with springs so that the door

47 is normally maintained in the closed position. This insures that the interior of the freezing container will be kept isolated from the atmosphere except when something is being placed in or removed from the freezing container. By this arrangement, the collection of frost upon the interior surfaces of the freezing container 28 will be minimized.

To cool the food compartment 32, the side and bottom wall portions 36 of the freezing container 28 are provided with refrigerant passages. The refrigerated plate 26 is likewise provided with refrigerant passages 48 of which the inlet end is connected to the capillary restrictor supply tube 24 while the outlet end is connected by the tubing 59 to the refrigerant passages 52 formed in the right side portion of the U-shaped outer walls 36 of the freezing container 28. The first portion of these passages 52 includes a liquid trap portion 54 which prevents liquid refrigerant from returning to the refrigerated plate 26 and subsequent passages which finally connect with the refrigerant passages 56 in the bottom wall portion of the U-shaped wall portion 36. These refrigerant passages 56 in the bottom wall portion connect with the vertical extending passages 58 in the left side portion of the U-shaped wall portion 36. The uppermost of these passages 58 connect directly with the suction conduit 69 which in turn connects to the suction inlet of the sealed motor compressor unit.

The refrigerated plate 26 has the edges spaced away from the sides and back walls of the freezing container 28 as well as from the door 47 at the front of the container. It is further isolated from the outer walls of the freezing container 28 by being supported by the insulating member 62 which rests upon the bottom wall portion of the U-shaped outer wall portion 36 of the freezing container 28. This refrigerated plate 26 is adapted to support a generous quantity of frozen foods such as the frozen food packages 64 as well as ice trays 66 which may be used for freezing ice and comestibles.

The sealed motor compressor unit 20 is supplied with electric energy through the supply conductors 68 under the control of the thermostatic switch 70 connected by a capillary tube 72 to the bulb portion 74 provided at a midportion on the left side of the U-shaped portion 33 of the freezing container 28. The thermostat switch 70 is adjusted so that it will not close until it has reached temperatures, for example, of 34° or 36° F. It however will open at a much lower temperature such as, for example, 10° F. This arrangement will insure that before the motor compressor unit 20 starts the refrigerated outer walls of the freezing container 28 must reach a temperature above freezing so that all frost thereon will melt.

The melted frost is collected in the tray 76 which is preferably made of a suitable thermoplastic thermal insulating material and provided with a drain spout 78 which discharges the frost water onto the side wall of the food compartment liner 46. This frost water is then drained from the bottom of the liner through the drain 89 into a cooling vessel 82 in the machine compartment 84 where the atmosphere is sufficiently warm and has sufficient circulation to evaporate the water from the pan 82.

Referring now to the Figs. 4 to 6 inclusive, there is shown a modification in which the refrigerant liquefying apparatus and the switch mechanism are omitted since they are like that shown in Figs. 75

1 to 3. Only the upper portion of the refrigerator cabinet 130 is shown as well as the upper portion of the cabinet door 134. This form differs from Figs. 1 to 3 in that there is provided a U-shaped continuous wall portion 136 which extends continuously, forming the side walls 137 and 139 as well as the back wall 138 of the freezing container 128. Sealed to the upper edges of this U-shaped wall portion 136 there is provided a top wall 140 which slopes from its center portion downwardly to the side portions so that melting frost will readily drain from it. The freezing container 128 is supported from the top wall of the food compartment liner 146 by the hangers 142 and 144.

The bottom of the freezing container 128 is enclosed and sealed by a member 162 of insulating material which has its upper portion fitting into and sealing against the lower edges of the U-shaped wall portion 136. The outer edges of this member 162 are provided with a trough 177 located beneath the lower edges of the wall portions 136 of the freezing container so that it will collect the frost water from the wall of the freezing container when the walls are defrosting. The trough 177 discharges into a spout 178, which discharges the frost water onto the wall of the food compartment liner 146 and disposes of it in the same manner as described for Figs. 1 to 3. Within the freezing container 128 there is supported upon the member 162 an extensive flat refrigerated plate 126 provided with refrigerant passages 148. This refrigerated plate 126 is spaced from the outer walls of the freezing container 128 and is adapted to support frozen food packages and the ice trays 166 in the same manner as Figs. 1 to 3.

Liquid refrigerant from the condenser is forwarded through the capillary restrictor tube 124 to the inlet end of the refrigerant passages 148 of the refrigerated plate 126 for supplying the refrigeration to the refrigerated plate and to the frozen food packages and the ice trays 166. The refrigerated plate 126 as well as the member 162 and the frozen food packages as well as the ice trays 166 constitute a relatively large mass having a high hold-over capacity which is cooled to a low temperature by receiving the refrigerant first from the capillary tube 124. This relatively high mass enables it to retain the relatively low temperature for considerable periods of time. From the refrigerant passage 148, the refrigerant then flows through the connecting tube 150 to the refrigerant passages in the U-shaped portion 136. In this U-shaped portion the refrigerant passages include a liquid trap portion 152 and refrigerant passages 156 which extend continuously through the U-shaped portion. As shown, they extend in serpentine fashion from one side wall across the bottom to the other side wall and back again. These passages 152 then connect with the passages 156 provided for cooling the top wall 140. The passages 156 then connect with the suction line 160 which connects to the suction inlet of the motor compressor unit.

The enclosure of the freezing container 128 is completed by the insulated freezing container door 147 hinged at the bottom to the insulating member 162. It is preferably provided with a gasket seal and springs for insuring that the door 147 is normally closed and normally seals the interior of the freezing container 128 from the atmosphere in the food compartment 132. As shown in Fig. 6, the member 162 may be made of an outer tray-shaped portion of thermoplastic

material with the trough 171 extending around the edges. Within the tray-shaped portion is provided thermal insulating material upon which the refrigerated plate 126 is directly supported. However, if desired, the member 162 may be made of a homogeneous material having thermal insulating properties.

The operation of the refrigerating system is controlled by a thermostatic switch connected in series with the sealed motor compressor unit in the manner shown in Fig. 1. The thermostatic switch is controlled by a volatile fluid in the capillary tube 172 having a bulb portion 174 clamped to the side wall portion 139 of the freezing container 128. The thermostatic switch is set to operate upon a defrosting cycle as in Figs. 1 to 3 so that before the motor compressor unit can start the outer walls of the freezing container 128 must rise to temperatures above 32° F., such as 34° or 36° F., so that they will be defrosted every cycle. These outer walls of the container 128 having a sufficiently low mass that they will warm up quickly to defrosting temperature while the interior of the freezing container by reason of the mass of the refrigerated plate 126 and the elements in contact with it will remain at temperatures below freezing.

In Figs. 1 to 6 the freezing container extends substantially all the way across the top of the food compartment. In Figs. 7 and 8 the freezing container 223 occupies less than half the upper portion of the food compartment 232 which is enclosed in the insulated cabinet 230. In the freezing container 228 there is provided a freezing evaporating portion 226 forming a bottom and the right side of the freezing container 228. It also includes two tray supporting portions 225 and 227 which may or may not be provided with a supply of liquid refrigerant.

The freezing evaporating portion 226 is provided with refrigerant passages 248 which may connect with the supports 225 and 227 if these tray supports are to be refrigerated by liquid refrigerant. Otherwise the trays 266 may receive their refrigeration by conduction through the metal of the supports 225 and 227 from the freezing evaporating portion 226. Beneath the metal tray supporting portions 225 and 227 there are shown frozen food packages 264 which are supported upon the bottom portion of the freezing evaporating portion 226. The freezing evaporating portion 226 is isolated from the atmosphere in the food compartment 232 by being enclosed on their outer surfaces by an insulating member 262.

The top and left side portions of the freezing container 228 are formed by the metal container wall portions 237 and 240. These extend into sealing engagement with the insulating member 262 but the freezing evaporating member 226 has its edges stopping short of the metal wall portions 237 and 240 so that the freezing container 226 is thermally isolated from the wall portions 237 and 240. The wall portions 240 and 237 are provided with refrigerant passages 256, the upper end of which connect with the upper end of the refrigerant passages 248 and extend continuously in serpentine fashion across the top wall 240 and the side wall 237 and finally connect with the suction conduit 260. The liquid refrigerant is supplied through the capillary restrictor tube 224 to the lower portion of the refrigerant passage 248 so that the frozen food packages 264 are always assured of an adequate supply of liquid refrigerant.

The refrigerating system is controlled by a

thermostatic switch in the same manner as Figs. 1 to 3. The thermostatic switch has connected to it a capillary tube 272 containing volatile liquid and connecting to a bulb portion 274 in direct contact with the side wall portion 237. As in Figs. 1 to 3 the thermostatic switch operates upon a defrosting cycle closing, for example, at 34° to 36° F. and opening at about 10° F. According to this arrangement, the outer surfaces of the freezing container 228 will be defrosted every cycle. The member 262 has sufficient insulating properties to keep its outer surface from collecting frost. The insulating member 262 is provided with a trough extending along one side which discharges into a compartment 271 provided in the tray 275 located beneath the cooling unit 228, and supported upon the shelf 273. The cooling unit 228 is enclosed at the rear by metal wall 228 and at the front by an insulated door 247 which may be hinged at the bottom, as shown, or at the side, if desired, to complete the sealing of the interior of the freezing container 228. This will substantially thermally isolate the interior of the container 228 and prevent moisture from migrating from the food compartment 232 into the interior of the container 228.

Thus in each of these forms, I have provided a refrigerator having a cooling unit in which the outer surfaces defrost automatically every cycle while the interior is maintained at freezing temperatures. Since all the refrigerated surfaces are a part of a single cooling unit the cost is relatively low.

In accordance with the provisions of Rule 78a, reference is made to the following prior filed applications: Serial No. 236,645, filed July 13, 1951; Serial No. 223,550, filed April 28, 1951; Serial No. 193,963, filed November 3, 1951.

While the form of embodiment of the invention as herein disclosed constitutes a preferred form, it is to be understood that other forms might be adopted, as may come within the scope of the claims which follow.

What is claimed is as follows:

1. In combination, an insulated refrigerator cabinet, a freezing container having metal container wall portions exposed to the atmosphere within said cabinet, said metal wall portions being provided with refrigerant passages, an extensive flat refrigerated plate within said freezing container for supporting ice trays and frozen food, the edges of said flat plate being spaced from the container wall portions, means for supplying liquid refrigerant first to said plate and thence to the refrigerant passages of said exposed metal container wall portions, control means responsive to the temperature of said metal container wall portions operating upon a defrosting cycle for controlling said refrigerant supply means, and insulating means between said plate and said exposed metal container wall portions.

2. In combination, an insulated refrigerator cabinet, a freezing container having metal container wall portions exposed to the atmosphere within said cabinet, said metal wall portions being provided with refrigerant passages, an extensive flat refrigerated plate within said freezing container for supporting ice trays and frozen food, insulating means substantially coextensive with said plate between said plate and said exposed metal container wall portions for providing a heat transfer barrier between said plate and said wall portions, the remaining interior surfaces of said container wall portions other than those covered by said plate being exposed

to the interior of said freezing container, means for supplying liquid refrigerant first to said plate and thence to the refrigerant passages in said exposed metal container wall portions, and control means responsive to the temperature of said metal container wall portions for controlling the supply of liquid refrigerant, said control means being set to operate upon a defrosting cycle to prevent the supply of liquid refrigerant to said refrigerant passages in said wall portions until said wall portions defrost and supply liquid refrigerant to the plate and the walls to cool both the plate and the walls below freezing temperatures, said plate having sufficient holdover capacity to prevent its defrosting at any time during normal cycling.

3. In combination, an insulated refrigerator cabinet containing a food compartment, a rectangular box-shaped freezing container having metal container wall portions of relatively low mass exposed to the atmosphere in said food compartment, at least two entire wall portions of said container being provided with refrigerant passages, a tray supporting refrigerant evaporating portion of relative high mass having a substantially flat refrigerated area located within the freezing container for supporting ice trays and frozen food packages, the edges of said tray supporting portion being spaced from said wall portions, insulating means for insulating said evaporating portion from said metal container wall portions, means for supplying liquid refrigerant first to said evaporating portion and thence to said refrigerant passages in the container wall portions.

4. In combination, an insulated refrigerator cabinet containing a food compartment, a rectangular box-shaped freezing container having metal container wall portions of relatively low mass exposed to the atmosphere in said food compartment, at least two entire wall portions of said container being provided with refrigerant passages, a tray supporting refrigerant evaporating portion of relatively high mass having a substantially flat refrigerated area located within the freezing container for supporting ice trays and frozen food packages, insulating means for insulating said evaporating portion from said metal container wall portions, means for supplying liquid refrigerant first to said evaporating portion and thence to said refrigerant passages in the container wall portions, said evaporating portion also having refrigerant passages, said refrigerant passages being unrestricted, a continuously open unrestricted connection connecting said passages in said wall portion and

5 said passages in said evaporating portion, and control means operating upon a defrosting cycle responsive to the temperature of a portion of said container wall portions for controlling the supply of refrigerant.

10 5. In combination, an insulated refrigerator cabinet containing a food compartment, a rectangular box-shaped freezing container having a U-shaped refrigerated metal container wall portion within and exposed to the atmosphere within said food compartment, an extensive flat refrigerated plate within said freezing container for supporting ice trays and frozen foods, insulating means between said plate and the wall portions of said container, said wall portions having continuously open unrestricted passages, a continuously open unrestricted liquid trap connection connecting said passages and said plate having means for preventing the flow of liquid refrigerant by gravity from said passages to said plate, means for supplying refrigerant first to said plate and thence to said U-shaped refrigerated wall portions.

20 6. In combination, an insulated refrigerator cabinet containing a food compartment, a rectangular box-shaped freezing container having a U-shaped refrigerated metal container wall portion within and exposed to the atmosphere within said food compartment, an extensive flat refrigerated plate within said freezing container for supporting ice trays and frozen foods, insulating means between said plate and the wall portions of said container, said wall portions having continuously open unrestricted passages, a continuously open unrestricted liquid trap connection connecting said passages and said plate having means for preventing the flow of liquid refrigerant by gravity from said passages to said plate, means for supplying refrigerant first to said plate and thence to said U-shaped refrigerated wall portions, and control means operating upon a defrosting cycle and responsive to the temperature of said U-shaped refrigerated wall portion for controlling the supply of refrigerant.

45 46 JAMES W. JACOBS.
